UNITED STATES PATENT OFFICE.

JAMES V. COOK, OF MILWAUKEE, WISCONSIN.

SHINGLE.

Application filed April 13, 1925. Serial No. 22,753.

This invention relates to shingles.

In shingles as heretofore constructed particularly the composition shingles, difficulty has been experienced due to the curling up 5 of the edges of the shingle either from warping or from the effect of wind. When it is considered that it is necessary to tack the shingles in place at a point spaced from the free edges thereof, it is readily apparent 10 that difficulty will occur in the use of this type of shingle.

This invention is designed to overcome the above noted defects, and objects of this invention are to provide a shingle which is 15 so formed that its exposed edge will not loosen or curl up or be blown up by the wind, but which will at all times remain in a flat condition, and in which no additional nails are employed and no exposed nails 20 appear.

Further objects are to provide a shingle which is of simple construction, and which may be readily and cheaply produced, and which may be quickly and easily applied.

25 An embodiment of the invention is shown in the accompanying drawings, in which:—

Figure 1 is a fragmentary view showing a number of shingles in position.

Figure 2 is a perspective view of one of 30 the shingles.

Referring to the drawings, it will be seen that the shingles comprise an upper body portion 1 which is substantially rectangular, and a lower exposed portion 2. The lower 35 portion is joined to the upper portion by means of a narrow tongue like member 3 which is provided with diverging sides 4. The lower portion 2 is further provided with upwardly projecting ears 5 on its inner side, such ears being spaced from the connecting 40 tongue 3. Preferably a pair of apertures 6 are provided for the nails and these apertures are located in the corners of the portion 1 preferably in the lower corners, as 45 illustrated.

Referring to Figure 1, it will be seen that a row of shingles are tacked down and the next row is positioned by first slipping the ears 5 beneath the slanting edges 4 of the 50 previously secured row. Thereafter, nails 6' are passed through the apertures 6 and extend through the body portions 1 of the lower shingles. Thus the lowest portion, or exposed portion 2 of the shingles is retained 55 by the interengagement of the ears 5 with the previously laid row of shingles. It is

to be noted that the nails in the previously laid row are fully and adequately covered by the succeeding row of shingles. Further, it is to be noted that the meeting edges of 60 the body portions 1 are covered by the superimposed shingles.

It is to be noted further that these shingles may be very rapidly laid and do not require any extensive operations in positioning them. 65 It is merely necessary, as previously stated, to slip the ears 5 into place and, thereafter, tack the shingle down.

It is to be particularly noted from reference to Figure 1 that the butt joints of one 70 row of shingles are wholly covered by the tongue 3 and the tab 2 of the superimposed shingles. Not only this, but also the tab 2 extends downwardly below the butt joint, as clearly shown in Figure 1. It is held 75 down by the underlapping of the tongues 5 beneath the tapered edges 4 of the lower shingles. This, therefore, attains the result that the butt joint is wholly covered not only on its upper side, but at its extreme end also, 80 by the projecting tongue 2. In this way no slots are presented to the weather so that, although a driving rain may impinge upon the shingles, it cannot be driven upwardly 85 between the butt joints of the body portions of the shingles, as their extreme edges even are not exposed.

It has been found that these shingles will not curl or turn up at their free edges even when subject to high wind pressures. 90 Further, these shingles may be cheaply manufactured and easily placed without requiring the services of a skilled operator.

Although the invention has been described in considerable detail, it is to be understood 95 that the invention may be variously embodied and is, therefore, to be limited only as claimed.

It is to be further noted that there are no 100 exposed corners so that no curling of the corners can occur as the corners are positioned beneath the adjacent row.

I claim:

A roofing comprising a plurality of shingles, each shingle having a body portion, a lower tab, a tongue joining such lower tab with the body portion and having a straight portion and a beveled portion, the beveled portions of each tongue forming obtuse angles with the lower edge of the rectangular body portion, said tab extending outwardly from the points of union with the 105 110

2
tongue and thereafter extending upwardly to form upwardly and outwardly projecting ears with the edges of the ears forming obtuse angles with the upper edge of the tab,
5 the shingles of one tier being arranged with their body portions forming butt joints, and the shingles of the superimposed tier extending completely over and beyond the edge of the butt joint, whereby the butt joints are

completely hidden from view, said tabs having their ears underlapped below the tapered portions of the tongues of the lower tier of shingles.

In testimony that I claim the foregoing I have hereunto set my hand at Milwaukee,¹⁰ 15 in the county of Milwaukee and State of Wisconsin.

JAMES V. COOK.
